UNITED STATES PATENT OFFICE

112,263

DESIGN FOR A WATCHCASE

Arthur W. Wadsworth, Fort Thomas, Ky., assignor to The Wadsworth Watch Case Company, Dayton, Ohio, a corporation of Kentucky

Application August 2, 1938, Serial No. 79,037

Term of patent 7 years

To all whom it may concern:

Be it known that I, Arthur W. Wadsworth, a citizen of the United States and a resident of Fort Thomas, in the county of Campbell and State of Kentucky, have invented a new, original, and ornamental Design for a Watchcase, of which the following is a specification, reference being had to the accompanying drawing, forming part thereof.

In the drawing:

I claim:

The ornamental design for a watchcase, substantially as shown.

ARTHUR W. WADSWORTH.
